BATHROOM UTILITY BAG

Corinne C. Blair, 5341 La Pasada St., Apt. 5,
Long Beach, Calif. 90815

Filed Jan. 10, 1968, Ser. No. 10,107

Term of patent 7 years

U.S. Cl. D87—5
Int. Cl. D3—99; D7—06

Fig. 1.

Fig. 2.

Fig. 3.

Fig. 4.

FIG. 1 is a front elevational view of a bathroom utility bag showing my new design;

FIG. 2 is a back elevational view thereof;

FIG. 3 is a side elevational view of the left side of FIG. 1, the opposite side being a mirror image of the side shown; and

FIG. 4 is a top plan view thereof.

I claim:

The ornamental design for a bathroom utility bag, as shown and described.
